[57] CLAIM

The ornamental design for the pliers, as shown and described.

DESCRIPTION

FIG. 1 is a plan view of the tool in a closed position;

FIG. 2 is a side view of the tool of FIG. 1;

FIG. 3 is a plan view of the tool of FIG. 1 in an open position;

FIG. 4 is an end view of the tool of FIG. 1 from the head end of the tool; and,

FIG. 5 is an end view of the tool of FIG. 1 from the handle end of the tool.

The characteristic feature of the design resides in the shape and configuration of the handles.
